(57) **CLAIM**

The ornamental design for a vehicle grille, as shown and described.

DESCRIPTION

FIG. 1 is a front and top perspective view of a vehicle grille, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion labeled, ‘FIG. 9’ in FIG. 1; and,

FIG. 10 is an enlarged view of a portion labeled, ‘FIG. 10’ in FIG. 2.

The broken lines in the figures illustrate portions of the vehicle grille that form no part of the claimed design. The dash dot dash lines in FIGS. 1, 2, 9 and 10 are for the purpose of depicting the boundary lines of the enlarged views and form no part of the claimed design.
